UNITED STATES PATENT OFFICE.

GEORGE H. FAHRENBRUCH, OF OMAHA, NEBRASKA.

CAR-DOOR.

1,369,229.

Specification of Letters Patent. Patented Feb. 22, 1921.

Application filed March 29, 1920. Serial No. 369,701.

To all whom it may concern:

Be it known that I, GEORGE H. FAHRENBRUCH, a citizen of the United States, residing at Omaha, in the county of Douglas and 5 State of Nebraska, have invented certain new and useful Improvements in Car-Doors, of which the following is a specification.

My invention relates to a new and useful improvement in car doors and to a type of 10 door shown in the patent granted to me on October 24, 1916, numbered 1,202,276.

In the present invention, however, two 15 sliding doors are shown and a movable center post, so that both doors may be moved to their open position and the center post slid back thereby forming a maximum unobstructed opening.

An object of the present invention is to provide a double door, a movable center post 20 and means for tightly locking the doors in their closed position.

Another object of the present invention is to provide doors that may be used on cars 25 for carrying general merchandise, refrigerator cars and also on cars for carrying grain, wherein a tight fitting door is very necessary.

Another object is to provide a door that 30 may be first moved slightly outwardly and then moved longitudinally of the car, the second door operated in the same way and the center post then moved to the side of the open door way.

Another object of the present invention is 35 to provide double doors that when placed in their closed position may be tightly locked in the casing and center post, so that none of the grain will be able to escape either from under the door or around its sides; 40 and to provide a locking mechanism that will tightly wedge both doors in position in the sills and center post and at the same time may be easily released to permit, if desired, but a slight opening of one or both doors, 45 or, both doors to be fully opened and the center post moved if desired.

Still another object of my invention is to 50 so construct the double doors that the locking mechanism need be applied to only one of them; this locking mechanism not only locking the door to which it is applied but also locking the other door and holding the center post tightly between them.

Still another object of the present invention is to construct the double doors and 55 movable center post so that only one of the doors may be opened if desired, the other being tightly held in place until the center post is moved.

Still another object is to provide double 60 doors, locking mechanism and movable center post that may be easily installed on cars in use as well as placed on new ones.

Another object is to provide a double door 65 that may be easily operated, fit snugly within the frame and so constructed that it will remain tight even after hard service.

With these and other objects in view, my 70 invention consists of certain new and novel construction and combination of parts as will hereinafter be more fully described and pointed out in the claims.

Referring now to the drawings forming 75 a part hereof and wherein I have shown a preferred form;

Figure 1 is a view in elevation, both doors being shown in their closed and locked position;

Fig. 2 is also a view in elevation, in this instance, however, the doors being open and 80 the center post slid to one side;

Fig. 3 is a vertical sectional view showing the door out and ready to slide;

Fig. 4 is an end elevation partly in section showing the center post;

Fig. 5 is a vertical sectional view of the door in closed position, a portion being broken away to show the locking groove;

Fig. 6 is a top plan view showing the doors and center post, the doors being in 90 their closed position;

Fig. 7 is a similar view, and showing how the door is first moved when desired to open the same; and

Fig. 8 is a view from the inside of the 95 car and at the top showing the guide rod for the center post.

Referring now to Fig. 1, there is shown a part of an ordinary box car 1, the door posts or stiles 2, and 3 and in the opening 100 between them are shown the two doors 4 and 5. It is to be noticed that one of the doors 4 is slightly larger than the other one and in some instances opening of but this door may be all that is necessary.

Located between these doors is the mov-

able center post 6, which is provided with a casting 7 at its lower end which engages with a guide rail 8, located just below the door sill 9.

5 In Figs. 4 and 8 is shown in detail this center post 6 and casting 7, on which is provided the outstanding lug 10 which passes beneath the above mentioned guide rail 8.

A casting 11 is also positioned at the top 10 of the center post which casting is provided with the upwardly and downwardly curved plate 12 which is adapted to bear against the inner surface of the top sill 13, so that the post cannot be forced outwardly. The 15 sill 13 may be provided with a plate 14 to protect the sill and to furnish a smooth bearing surface for the plate 12.

A guide rail 15 is placed on the top sill 20 over which passes the downwardly extending portion of the plate 12 and a yoke arm bracket 12' is bolted to the post 6, into which arm fits the lower edge of the plate 12, thereby tightly retaining the post against lateral movement.

25 Located directly under the center post, when the same is in its normal position, is the member 16 which is riveted or bolted to the car, the said casting being formed with the slot 18 so that the lug 10 of the 30 casting on the center post may pass within the same.

The upper inner surface of this member 16 bears against the guide rail 8 and may be riveted or bolted thereto.

35 From the above it will be seen that a 40 slideable center post is provided having means at both its upper and lower ends for its guidance and also that the member 16 last mentioned will greatly reinforce the post when in its set position, so that even though a heavy load be placed against the same it will not be forced outwardly from its set position. At the same time, however, it may be easily moved longitudinally 45 of the car when desired.

This center post may be completely reinforced with a metal sheathing 19 or metal plates may be applied to its surface, and on 50 its opposite sides are formed the vertical grooves or channels 20 (Figs. 6 and 7) into which fit the adjacent sides of the doors 4 and 5 when the doors are in their closed position.

Referring now to the doors 4 and 5 and 55 the manner in which they are hung and operated it will be seen (Figs. 1, 2 and 3) that a rail for supporting the hangers is shown that extends the width of the door opening and for some distance on either side thereof. This rod 21 is securely bolted to the car body as it supports both doors and is of such strength that it will not permit of any sagging of the doors.

60 Referring now to the hangers 22 there are four provided, two for each door, the upper

ends of each being provided with wheels for engaging the rail 21, while the lower ends are provided with eyelets 23 so that pins 25 may be passed through standards 24 fastened to the door and the said eyelets 23, to 70 provide a pivotal movement and allow the doors to fit back into the sills and center post. The hangers are of sufficient length, and the standards placed a substantial distance from the top of the door so that this 75 is possible.

The door 4 has its one edge 26 rounded to fit within the vertical groove 20 in the center post 6, while its other edge 27 is slightly tapered to fit snugly against the walls 28 of the sill 2, the inner edge of the door abutting against the slightly outstanding wall 29. (Figs. 6 and 7.)

It might be here mentioned that the bottom sill 9, the bottom of the casting 7 on 85 the center post 6 and the bottom of the doors are cooperatively tapered so that the doors fit tightly in place at their bottom when locked in position while the center post at its bottom fits snugly with the bottom sill so that if grain is carried it will 90 not escape under either the doors or center post.

The other door 5, however, is rounded at both its edges 30 as one edge is to be received in a channel or groove 31 formed in the post or stile 3 while its other edge is to fit within one of the channels 20 in the center post 6.

Referring now to the manner of locking 100 the door 5 which in turn will hold both doors in place, an arm 33 is shown adjacent the right hand side of the door which is vertically disposed and which is connected at its upper and lower ends to the bell crank 105 levers 34 which are pivotally mounted at 35.

Two short arms 36 are connected to the respective bell cranks and to their outer ends are fastened the vertically positioned roller 37 which is adapted to wedge against the 110 side of the door and into a groove 38 formed in the stile 2.

The lower bell crank lever has a downwardly extending arm 39 formed therewith which when forced upwardly (Fig. 1) will 115 withdraw the roller 37 from the groove 38, the weight of this arm normally forcing the roller to its locked position.

A locking mechanism of this kind not only holds the door from longitudinal movement but also forces it inwardly, forming a tight fit on the bottom sill 9 and against the wall on the stile 2. It will also jam the center post tightly between the doors 4 and 5 holding all three tightly in place.

120 Of course the width of the opening and the width of the doors and center post is such that when the doors are in their closed position even before the locking mechanism is operated the doors and post will just fit, 130

the locking mechanism when operated further pressing the door 5 into a tight and snug closed position.

Secured to the door 4 is a chain 40, the outer end of which slides along the rod 40' so that the lower end of the door may move only slightly outwardly, and a similar chain is fastened to the other door and passes around the guide 8.

10 On each door a couple of handles 42 are provided which are to be grasped when the doors are to be moved.

The operation of the doors is therefore as follows: Supposing that the doors are closed and locked as shown in Fig. 1. To open them, first the handle 39 will be forced upwardly which will remove the roller 37 from its jammed position between the door and the walls of the groove 38. The handles 20 42 on the door 4 may then be grasped and the right hand side of the door moved to the position shown in Fig. 7.

The door will then be moved slightly forwardly until its rear edge may be removed 25 from the channel 20 in the center post 6. The door will then be in the position shown in Fig. 3 and ready to slide forward away from the opening, as shown in Fig. 2.

To open the smaller door 5, the center 30 post will be moved slightly to the right so that the edge will be removed from the channel in the center post and then this door may be moved slightly outward at its right hand side, then slightly forwardly so that the 35 other edge will slip from the channel in the sill 3 and after it has been moved outwardly beyond the frame it may likewise be pushed rearwardly out of the way.

The center post may then be pushed back 40 out of the way against the sill 3 leaving an unobstructed opening.

If the car were full of grain the large door could be opened to first the position shown in Fig. 3, that is, not moved forwardly of the car, until the grain ceased to flow, when it would be opened and moved forwardly as much as desired.

The operation to close and lock the doors is just the reverse of the above, the roller 50 37 tightly wedging the door 4 against longitudinal movement, forcing the door 4 also well up on the sill and preventing any lateral movement, while also tightly jamming the center post between the double doors.

55 From the foregoing it will be seen that I have provided a double door that is capable of general application.

It may be used on cars for carrying grain as the doors are arranged to prevent any 60 loss either at the side or beneath the same.

Also it can be equally as well used on cars for carrying automobiles, refrigerating cars or cars carrying general merchandise; both doors may be slid beyond the opening 65 and the center post moved to one side.

Furthermore the doors and center post present a strong construction which is not generally possible in sliding doors, and at the same time the different guides employed prevent any undesirable lateral movement of either the doors or center post.

Having thus described my invention, what I claim as new and desire to secure by Letters Patent is:-

1. The combination with a door frame 75 having stiles, sliding doors and hanging means for said doors arranged to permit a slight lateral movement of said doors, a center post also slidingly mounted in said frame and means for locking one of said doors to thereby force the door inwardly and lock the other of said doors and the center post in position.

2. In combination with a door frame having stiles, sliding doors, hanging means for 85 said doors to permit a slight lateral movement of said doors, a center post also movably mounted in said frame and means for preventing any lateral movement of the same, locking means secured to one of the 90 doors for forcing the same inwardly for tightly holding the two doors and center post in a locked position.

3. In combination with a door frame having stiles, sliding doors and hanging means 95 secured thereto and arranged to permit a slight swinging and lateral and then sliding movement of the doors, a sliding center post, means for locking the doors and center post in position and said center post being 100 capable of being moved to one side of the door frame when the doors are opened and tongue and groove coöperation between the frame doors and center post.

4. In combination with a door frame, 105 sliding doors, hanging means pivotally secured to the upper portion of the doors permitting a slight lateral movement of the doors and said doors when hanging in a vertical plane with the hangers being out beyond the door frame, a movable center post and means at the top and bottom thereof for preventing any lateral movement of the same and reinforcing means opposite its lower end when in its set position to further prevent any lateral movement, and means for locking the doors and center post in their normal closed position.

5. In combination with a door frame, a movable center post, two doors, the said center post when in position holding one of said doors against movement, the other door capable of being shut and opened without moving said center post and means for locking the last mentioned door in the frame 115 and center post to thereby jam the two doors and center post into substantially a composite unit.

6. In combination with a door frame having stiles both of which are provided with 120

grooves, doors movable in the frame, a center post provided with grooves on its opposite sides and said center post also movable in said frame, one of said doors having a member 5 movably mounted thereon and adapted to enter the groove in the adjacent stile, means mounted on the door for operating the member whereby the door is forced edgewise into a groove in the center post and 10 sidewise in the said adjacent stile and the other door held by the center post and remaining stile.

7. In combination with a door frame, having stiles both of which stiles are provided with vertically extending grooves, doors movable in the frame, a center post also provided with vertically extending grooves on its opposite sides and said center post also movable in said frame, one of said doors having a locking member mounted thereon, adapted to enter the groove in its adjacent stile whereby the door is forced edgewise into a groove in the center post and sidewise into the adjacent stile, the other 25 of said doors fitting within a groove in the center post and a groove in its adjacent stile and securely held in position by locking the first mentioned door.

8. In combination with a door frame having stiles both of which are provided with grooves, the groove in one of the stiles being longer than the other, and the stile with the shorter groove provided with a flange, doors movable in the frame, a cen-

ter post also movable in said frame and provided with grooves on its opposite sides, one of said doors having a locking member thereon adapted to enter the shorter groove, whereby the door is forced edgewise into the groove in the center post and sidewise in 40 the stile with the shorter groove, and against said flange, the other door fitting within the stile with the longer groove and in the remaining groove in the center post, both doors and the center post all held tightly 45 in position when the door with the locking member thereon is forced into place.

9. In combination with a door frame having stiles, one of said stiles provided with a groove therein and the other of said stiles having a relatively short locking groove formed therein, doors within said frame and hung so that they may move slightly laterally and forwardly and rearwardly, a center post also movably mounted in said frame 50 and adapted to be moved to one side of the door frame when not in use, said center post provided with grooves on its opposite sides, means on one of said doors for entering the short locking groove to thereby 55 force the door edgewise in the center post and sidewise in its adjacent stile, the other of said doors fitting within the groove in its adjacent stile and in the groove in the center post and held against movement until 60 said center post is moved slightly forwardly.

In testimony whereof I affix my signature.
GEORGE H. FAHRENBRUCH.
